UNITED STATES PATENT OFFICE.

LOUIS B. CASSELL, OF DECATUR, ILLINOIS.

AUTOMATIC ADJUSTABLE AUTOMOBILE CAMPING TOP.

Application filed May 28, 1923. Serial No. 641,830.

To all whom it may concern:

Be it known that I, LOUIS B. CASSELL, a citizen of the United States of America, and a resident of Decatur, Illinois, have invented 5 a certain new and useful Improvement in Automatic Adjustable Automobile Camping Tops, of which the following is a specification.

This invention relates to the devices for 10 use in automatic adjustable automobile camping tops for use on all makes of cars wherein the convenience and comfort of tourists and campers is considered, the invention having particular reference to the provision 15 for the quick and automatic adjustability of the top.

An object of this invention is to provide 20 a top usable upon any make of automobile having enclosed sides, and to be so constructed that the said top may be readily and automatically adjusted so as to obviate the necessity of providing tents and the consequent numerous and burdensome accoutrements, and to provide a means whereby the 25 said top may be adjusted without the necessity of having to handle and put in place various parts and pieces relative to the adjusting operation, there being no separate metal or wooden parts of any kind which 30 can possibly become detached or require handling whether the top is open or closed.

Another object is to provide a means of 35 adjustment whereby the top may be adjusted to camping position without tools, by one person, and without leaving the seat of the car, as the simple mechanism which automatically adjusts the top may be operated from a seated position if desired, said mechanism being contained beneath the floor of 40 the car in such a manner as to be accessible from a small and inconspicuous trap door, thus enabling the operator to accomplish the adjustment in approximately thirty seconds or a fraction of the time required to insert 45 and arrange arms, braces, pegs, ropes, etc., incidental to hand means of arranging a covered camping top.

A further object is to provide a means of automatic adjustment which will be so

constructed that the adjusting stays shall be 50 permanently secured to and constitute one piece with the said top, being movable simultaneously therewith, and being of such sturdy construction as to obviate all possibility of damage by wind or any other reasonable strain to which said top may be subjected. Also to provide a braced and adjustable top wherein the bracing and adjustable features are carried concealed within 55 their natural environments.

In the accompanying drawings Fig. 1 is a fragmentary face elevation of the propelling mechanism which is concealed beneath the car floor, being attached to and operating through and upon both sides of the gear beam, the gear handle being shown in an upright position and also by dotted lines which indicate the natural positions of said gear handle while operating or concealed. Fig. 2 is a fragmentary sectional view showing the natural position of the various members of the device when the top is closed. Fig. 3 is a combination sectional view and fragmentary elevation showing the natural position of the propelling mechanism when 70 in readiness to open the car top, and the natural position of the various members of the front and rear elevating details of the device when the top is closed. Fig. 4 is a fragmentary plan view showing the propelling 75 mechanism in readiness to open the car top, and also a portion of both sides of the car walls indicating the relative position of the propelling chains and adjusting stays of the device when the top is closed. Fig. 5 is a fragmentary sectional view showing the natural 80 position of the various members of the device when the top is open, the propelling mechanism being omitted therefrom. Fig. 6 is a fragmentary elevation showing the natural 85 position of the various members of the device when the top is open, the propelling mechanism being omitted therefrom. Fig. 7 is a fragmentary cross-section of the wall 90 of the car showing the relative position of the various members involved in the wall mechanism. Fig. 8 is an exterior view of an automobile showing the top open with ordinary sectional drop curtains in place upon 95

one side and rear of the top, the sectional drop curtains for the front and foremost side being shown in a rolled-up position just within the edge of the top where such curtains are ordinarily carried. Fig. 9 is an exterior view of an automobile showing the top closed for touring and illustrating that this invention does not, when applied to any standard make of car, cause the car to differ in appearance from any other having a permanent top built on at the factory. Fig. 10 is a cross-sectional view showing the adjusting device installed, the gear handle 3 being turned completely down, shown by dotted lines 16, in Fig. 1, top closed for traveling. Fig. 11 is a cross-sectional view showing the adjusting device installed, the gear handle 3 being in position preparatory to adjustment as shown in Fig. 1, and the top open for camping.

In the drawings, the numeral 1 indicates a ratchet wheel mounted on a shaft 2 adapted to be rotated in a forward direction by means of suitable actuating means, comprising in the present instance a pawl 4 mounted on a lever 3 which projects through an opening into the body of the automobile, within easy access of the driver. The pawl 4 is held in engagement with the teeth of the ratchet wheel by means of a spring 6 attached to the pawl 4 at one end and to the lever 3 at the other end. A dog 5 pivotally mounted in a floor supporting beam 13, and held in engagement with the teeth 8 of the ratchet wheel by means of a spring 7 is provided to hold the ratchet wheel normally against backward rotation. Connected to a bell crank lever 9 is a lifter rod 10 for lifting the pawl 4. Mounted on each side of the floor beam 13 is a metal plate 11, secured to the beam by means of bolts 12. As illustrated, the lever 3 projects through an open slot in the automobile body floor 14, which slot permits the driver to withdraw the lever to the position indicated by the dotted lines 15, preparatory to propelling the ratchet wheel 1 in a forward direction, as will later be described, the forward positions of the lever 3 being indicated by dotted lines at 16.

Extending upwardly from the floor 14 are studs 17 to which the outer and inner walls of the automobile body are secured. Secured to the studs 17 at each end thereof are blocks 18 to each of which is fastened by means of bolts 20 a guide 19 for one of the slidable top supporting stays 23. These stays at their upper ends pass through slotted plates 21 secured to the top supporting sills 22.

The interior wall 24 of the body extends from the floor 14 to the upper edge of the sills 22. The exterior wall 25 extends from the lower edge of the floor beams 13 to the upper edge of the sills 22. The adjustable

top comprises the interior wall, or veneer 26 secured to the lower edges of supporting beams 27 and an exterior wall, or veneer 28 also secured to these beams.

Journalized in a hanger attached to the bottom side of the floor 14, at each side of the body of the automobile is a chain, or cable, pulley 29. A similar pair of pulleys 30 is secured to the bottom side of the sills 22, these pulleys supporting chains, or cables, 39 and 41 which are secured to spools, or drums, 35 and 37, respectively, mounted on the shaft 2. The chains, or cables, 39 and 41 extend from the spools 35 and 37 over the upper pulleys 30 and thence downwardly to tie caps 34 secured to the lower ends of the stays 23, so that these stays may be lifted by means of the chains when it is desired to elevate the automobile top. A similar arrangement of pulleys 31 and 32, and chains, or cables, 40 and 42 extending from spools 36 and 38 is provided for the top supporting stays 23 at the other end of the automobile body. It will be observed by reference to Figs. 8, 10 and 11 that there are two pairs of oppositely disposed top supporting stays 23, one pair located near each end of the body. It will be further observed that the chains, or cables, 39 and 41 are attached to the front stays and the chains, or cables, 40 and 42, to the rear stays, each chain of a pair being so wound on its spool as that rotation of the shaft 2 in a forward direction will cause each chain to be wound on its spool simultaneously to lift all the stays 23 and thus elevate the automobile top.

The entire apparatus is so constructed and arranged that the supporting stays, pulleys, chains and spools and also the ratchet and pawl are concealed either beneath the floor or within the walls of the body, so as to give the automobile body a neat and pleasing appearance.

In adjusting the top from a closed to an open position the ratchet handle 3 is drawn back to a position as indicated by dotted lines 15, engaging the ratchet teeth 8 with the pawl 4 and propelling said ratchet handle 3 to an opposite position longitudinally with beam 13, thus turning the ratchet which engages shaft 2 which in turn engages the spools 35, 36, 37, and 38 which thereby engage and wind upon themselves the chains 39, 40, 41 and 42, the chains 39 and 41 extending horizontally from the upper and lower sides respectively of spools 35 and 37 to and engaging the front base pulleys 29 on opposite sides of the car beneath the floor 14 and extending thence vertically upward, engaging the pulleys 30 in opposite walls of the car, fastened to and beneath the sills 22 between wall beam 17 and adjusting stay 23, extending thence vertically downward parallel with the edge

of adjusting stay 23 to the chain tie cap 34 which engages the chain terminal securely upon the base end of said adjusting stay 23. The chains 40 and 42 extending horizontally from the upper and lower sides respectively of spools 36 and 38 to and engaging the rear base pulleys 31 in opposite walls of the car beneath the floor 14 and extending thence vertically upward, parallel with the edge of adjusting stay 23, through an aperture provided in sills 22 in opposite walls of the car, engaging the main rear top pulleys 32 which are inset in said sills 22, and thence horizontally, within the chain grooves 43 provided in the top surface of said sills 22 between main rear top pulleys 32 and subordinate rear top pulleys 33 in opposite walls of the car, engaging said subordinate rear top pulleys 33, and thence vertically downward parallel with the edge of adjusting stay 23 to the chain tie cap 34 which engages the chain terminal securely upon the base end of said adjusting stay 23. Thus, the various mechanical members are propelled a certain distance within their natural environments, the clutch dog 5 by means of clutch dog spring 7 checking into the consecutive grooves between the ratchet teeth 8 engaging the same and thus holding the ratchet 1 in a stopped position until the ratchet handle 3 may again be brought back into the position as shown by the dotted lines 15 preparatory to further operations for the purpose of opening or elevating the car top.

In adjusting the top from an open to a closed position the ratchet handle 3 is grasped by the hand and propelled to a position to release clutch dog 5 which is then held in a position free from contact with ratchet teeth 8 by means of thumb pressure upon its handle at which time the ratchet handle 3 is moved, followed by the movement in a like direction of ratchet 1 upon shaft 2, being propelled by the force of gravity resulting from the weight of the car top suspended by and upon the various mechanical members of the adjusting mechanism, to a position as indicated by the dotted lines 15 when the clutch dog 5 is released and again permitted to engage the ratchet teeth 8, permitting ratchet handle 3 to be moved to an opposite position longitudinally with beam 13 without propelling the ratchet 1 by means of being released from propelling contact therewith by a slight pressure upon ratchet lever 9 which engages lever rod 10 which engages and lifts main dog 4 out of contact with ratchet teeth 8. Thus, the various mechanical members are propelled a certain distance within their natural environment for the purpose of closing or lowering the car top, the opening and closing action of the propelling mechanism being repeated from one to

twelve times in the respective instances, the number of times being governed by the amount of adjustment desired.

I claim:—

1. In an automobile body, the combination of an automatic adjustable camping top therefor having lifting and supporting means concealed within the walls and beneath the floor of said body, said means comprising vertical supporting members carried by said top and slidably mounted in fixed guides; chains or cables connected to said supporting members, spools rotatably mounted beneath the floor of said body upon which said chains or cables are adapted to be wound to lift said camping top, ratchet means for rotating said spools and a manually operable dog for holding said spools against rotation in the opposite direction, said camping top being adapted automatically to return by gravity to its closed position when said dog is released from engagement with said ratchet means.

2. In an automobile body, the combination of an automatic adjustable camping top therefor having lifting and supporting means concealed within the walls and beneath the floor of said body, said means comprising vertical supporting members carried by said top and slidably mounted in fixed guides, a shaft journaled in bearings secured to the under side of said floor, spools mounted on said shaft, lifting and supporting chains or cables adapted to be wound on said spools and connected to the lower ends of said supporting members, supporting pulleys for said chains or cables, a ratchet wheel for propelling said shaft in one direction and a dog for holding said shaft against rotation in the opposite direction, said camping top being adapted automatically to return by gravity to its closed position when said dog is released from said ratchet wheel.

3. In an automobile body, the combination of an automatic adjustable camping top therefor, having lifting and supporting means concealed within the walls and beneath the floor of said body, comprising a pair of vertical supporting members for each end of said top slidably mounted in guides within the walls of said body, pairs of spools mounted on a shaft journaled in bearings secured to the under side of the floor of said body, pairs of chains or cables wound upon said spools and connected to the corresponding lower ends of said top supports, each pair of chains or cables being wound on said spools in oppositely disposed relation to each other and adapted simultaneously to lift said supporting members and said top when the shaft carrying the spools is rotated in one direction, chain or cable supporting pulleys mounted in said body, a ratchet device for lifting and supporting said top in an elevated position, said ratchet

device comprising a ratchet wheel mounted on said shaft, a lever mounted on said shaft and extending into the interior of said body, a pawl carried by said lever adapted to propel said ratchet wheel in one direction and a dog pivotally mounted on said body and engaging the teeth of said ratchet wheel to hold said wheel against rotation in the opposite direction, said top being adapted to 10 return automatically by gravity to its closed

position when said dog is released from said ratchet wheel.

In testimony whereof I have hereto affixed my signature in the presence of two witnesses.

LOUIS B. CASSELL.
